UNITED STATES PATENT OFFICE.

JOHN F. SIMONS, OF PHILADELPHIA, PENNSYLVANIA.

DESIGN FOR A DISPLAY-BOX.

SPECIFICATION forming part of Design No. 30,859, dated May 23, 1899.

Application filed April 26, 1899. Serial No. 714,586. Term of patent 7 years.

To all whom it may concern:

Be it known that I, JOHN F. SIMONS, of Philadelphia, Pennsylvania, have invented a new and useful Design for Display-Boxes, of which 5 the following is a specification.

The essential feature of the design resides in the shape of the box, which when arranged in an upright position, standing or resting on one end, has a contour of substantially the same shape as the vertical shape of a thimble.

The design is shown in the accompanying drawing, which shows a perspective view of a box embodying the same.

The box consists of a bottom A, having four 5 outwardly-projecting walls B, C, C, and D, of which the base-wall B is substantially straight, the side walls C C are tapered or converge toward one another toward the top, and the top wall D is arched or curved, the said four walls

B, C, C, and D forming the general outline of 20 the vertical section of a thimble.

Lying within the box, at an elevation above the bottom and extending between the walls B, C, C, and D, is a piece E, having a series of inverted-U-shaped openings e. 25

Having now described my design, I declare that what I claim as new, and desire to secure by Letters Patent, is—

The design for a display-box substantially as described and as shown in the accompanying drawing. 30

In testimony of which invention I have hereunto set my hand.

JOHN F. SIMONS.
